DISTILLATION APPARATUS WITH
INTERNAL DECANTER

Bronson C. Skinner, Dunedin, Fla., assignor to
Clinton Foods Inc., New York, N. Y., a corpora-
tion of Delaware

Application December 22, 1949, Serial No. 134,498

3 Claims. (Cl. 202—204)

1

The present invention relates to apparatus for separation of liquids of different specific gravities and vapor pressures and, more particularly, to such apparatus which can be employed to advantage to separate oily and watery substances with utilization of principles of vacuum distillation and condensation.

A general object of the present invention is to provide such apparatus which is simple in construction, economical to build and easy and cheap to operate while effectively separating lighter liquids from heavier liquids with efficient provision for automatic return to the body of the heavier liquid of any desired part of a fraction thereof which may be carried off with the lighter liquid during initial operations within the apparatus.

A more specific object of the invention is to provide such a piece of apparatus which is self-contained and which efficiently will separate liquid of certain specific gravity and vapor pressure from heavier liquid having a lower vapor pressure by vacuum distillation and condensation to separate all of the lighter liquid with a fraction of the heavier liquid as a rich mixture from the remainder or main body of the latter, and which then automatically separates the components of the rich mixture by floatation with return of heavier liquid to its main body in a unique and simple manner.

A further object of the invention is the provision of such apparatus which may be used efficiently to separate oily substance comprising terpenes from fruit juices at undamaging temperatures, such as the removal of peel oil from citrus fruit juices, and which is vastly simpler than the complicated and very costly equipment commonly used for like purpose, the replacement of which constitutes one purpose of this invention.

Another object of the invention is to provide a structural embodiment thereof which may be readily constructed and which permits efficient use and operation thereof.

Other objects of the invention will in part be obvious and will in part appear hereinafter.

The invention accordingly comprises the features of construction, combination of elements and arrangement of parts, which will be exemplified in the construction hereinafter set forth, and the scope of the invention will be indicated in the claims.

For a fuller understanding of the nature and objects of the invention, reference should be had to the following detailed description taken in

2

connection with the accompanying drawings, in which:

Fig. 1 is a diagrammatic elevational view of parts of a typical citrus juice canning plant employing an embodiment of the apparatus of the present invention;

Fig. 2 is an enlarged side view, with parts in section and broken away, showing certain evacuating and control structure of apparatus of the present invention;

Fig. 3 is an elevational section of the embodiment of the device of the present invention shown in Figs. 1 and 2;

Fig. 4 is a view similar to Fig. 3 showing a modified form of the apparatus of the present invention;

Fig. 5 is a sectional view taken substantially on line 5—5 of Fig. 4;

Fig. 6 is an elevational view, with parts broken away, of certain of the elements of the floatation separator employed in the embodiment shown in Figs. 4 and 5, and with the outer casing vertically broken away and sectioned to show those parts;

Fig. 7 is a sectional view taken substantially on line 7—7 of Fig. 4; and

Fig. 8 is a fragmentary sectional view of parts of the condenser shown in Fig. 3, indicating the use of the lower jacket duct as a cooling water inlet, equipped with a flow regulating valve.

Referring to the drawings, like numerals identify similar parts throughout and, as will be seen from Fig. 1, a typical plant layout for removing peel oil from citrus fruit juices for the purpose of reducing peel oil content of fresh juice to be canned may comprise a juice storage tank 10, a pump 11 connected in a pipe line 12 leading from the storage tank to a flash pasteurizer 13. The outlet of the latter is connected by a pipe line 14 to the inlet of de-oiler apparatus 15 of the present invention. The outlet of de-oiler 15 is connected by pipe line 16 to a known type of can filler 17.

As will more fully appear by reference to Figs. 2 and 3, de-oiler 15 preferably comprises a cylindrical casing or tower shell 18 having a coned bottom 19 centrally ported and connected to the outlet pipe 16. In the form shown in Figs. 1, 2 and 3, the de-oiler casing 18 may be reduced in section at 19 to accommodate a reflux condenser 20 of lesser diameter than chamber 21 provided within the hollow casing. Preferably the lower portion of the casing 18 is made in sections, as shown in Fig. 3, with sections 22 and 23 meeting and preferably bolted together at 24 to facilitate

tate mounting parts within the chamber 21. The reflux condenser 20 is also preferably made as a separate unit, comprising a water jacket 25 fitted with header plates 26, 26 in which are mounted a plurality of open-ended vertical tubes 27-27, and that reflux condenser heat exchanger is mounted and preferably bolted to the top of section 23 at 28. A cool water supply pipe 29 may supply cooling water to the top of the jacket 25 and outlet pipe 30 may discharge the cooling water therefrom, but it is to be understood that the flow of water through the condenser may be reversed if desired. A dome 31 preferably caps over the top end of condenser unit 20 by being bolted to the top end thereof, and the interior of that dome may be communicated through a collar 32 with a steam injector or jet 33, bolted together as shown. Jet 33 is provided with a steam supply inlet 34 and has an outlet 35 open to atmosphere, for the purpose of evacuating the interior of the casing or tower 18.

The degree of evacuation within the casing 18 may be automatically controlled by a pressure regulator of known type or by automatic control of the rate of flow of cooling water through the condenser as will appear hereinafter. For example, there may be installed at 36 a pressure regulator of the diaphragm type which, as is best seen in Fig. 2, may comprise a relief pipe 37 connected into the side of collar 32 and fitted with a valve 38 having an air intake port 39. Valve 38 is suitably connected by linkage 40 to a diaphragm 41 in a diaphragm chamber 42. Pipe 43 connects pipe 37 to the compartment of chamber 42 on the side of diaphragm 41 opposite the connection of linkage 40 thereto so as to reduce the pressure in that compartment as a vacuum is drawn in the casing 18 by the steam jet 33. A weighted lever 44 pivotally mounted to linkage 40 opposes the force applied to diaphragm 41 by the evacuation in the top compartment of chamber 42. Thus, with adjustment of the weight on lever 44, the degree of evacuation in casing 18 may be predetermined and automatically maintained at such predetermined value, since that diaphragm pressure regulator will permit a controlled rate of flow of air into port 38 with undesirable increase in evacuation by steam jet 33. If desired, there may be substituted for pressure regulator 36 a regulator 45 of any well-known type, such as a spring loaded regulator, connected into the side of the chamber 21, as suggested in Fig. 3.

Within the chamber 21 there is mounted a floatation separator 46 which may comprise a cylindrical container 47 having a bottom 48, with its open top closed off by a collecting funnel 49. The container 47 is spaced on at least one side from the inner wall of shell 18 and preferably is concentrically and coaxially mounted within the chamber 21 by means of a supporting spider 148 having the arms thereof mounted to or on the inner surface of the casing wall to permit fluid passage. Collecting funnel 49 is of substantially greater diameter at its mouth than the diameter of a circle circumscribed about the outermost condenser tubes 27-27 so that drippings therefrom will fall into the funnel mouth. Funnel 49 is provided with a discharge tube 50 preferably closed off at its bottom end by plate 51 and provided immediately thereabove with a plurality of outlet holes 52-52 to assure discharge into container 47 in horizontal directions.

A stand pipe 53 has its open top inlet end 54 located at a point appreciably above the bottom 48 of container 47 to determine an interface or water level "WL." The bottom end of stand pipe 53 extends down through container bottom 48 so that its open discharge end 55 will spill liquid directly into the bottom of casing 18. Another stand pipe 56 is similarly mounted in container 47 with its open top intake end 57 located at a point above interface level "WL," such as a distance of about one-half inch (1/2"), to predetermine collection level "OL" of a lighter liquid. Open discharge end 58 of stand pipe 56 extends down through container bottom 48 to spill into an open top receptacle or cup 59 having a discharge tube 60 connected thereto and leading through the bottom of casing 18. A guard or baffle tube 61 is placed about stand pipe 53 and preferably is mounted coaxially therewith with its upper end extending above "OL" by support of its bottom end on the container bottom 48. Suitable inlet holes 62-62 are provided in the bottom of baffle tube 61 to permit passage of heavier liquid in the bottom of the container 47 into the space between outlet stand pipe 53 and that tube.

It will be noted that the floatation separator cylindrical container 47 is spaced laterally inward of the inner walls of chamber 21 an appreciable distance. This space is provided so that the spaces between the arms of support spider 148 may cooperate therewith in providing for fluid passage between the bottom portion of casing 18 and condenser unit 20. The bottom portion of chamber 21 defined below floatation separator 46 and its support spider 148 constitutes an explosion area or compartment 63 into which the outlet of stand pipe 53 spills and into the side of which is tangentially let supply or inlet duct or pipe 14 for the purpose of feeding thereto heated juice or liquid mixture. The tangential arrangement of the connection of supply pipe 14 with compartment 63 at 64 is preferred in order to discharge under relatively high pressure the heated liquid mixture along the circular wall of that compartment, to cause a swirling action of the liquid sprayed thereinto, thereby facilitating evaporation.

The operation of apparatus of the present invention, an embodiment of which is shown in Fig. 3, may best be understood by a description of a typical operation of a plant set-up similar to that shown in Fig. 1 when employed for the purpose of de-oiling citrus fruit juice. Government regulations for Grade A orange juice permit a tolerance of orange peel oil, comprised chiefly of terpenes, of 0.03%, and similar requirements are made relative to grapefruit or blended mixtures thereof. For the purposes of improving flavor, it is desirable to have an amount of the peel oil up to the tolerance limit present. Further, it is not desirable to de-oil all of the juices since loss of delicate flavoring principles, such as aldehydes and esters may be attendant upon de-oiling. Accordingly, it has been found to be desirable to de-oil only a portion of fresh juice and then mix that portion with another portion of fresh juice which has not been de-oiled. In a typical run, fresh orange juice may, for example, contain about 0.04% peel oil, and it may be desired to reduce the oil content to below the tolerance limit, such as to 0.02%. Accordingly, fifty percent (50% of the fresh juice will be de-oiled and then mixed with another fifty per cent (50%) of fresh juice which has not been de-oiled.

The fresh juice which is to be de-oiled is kept in storage tank 10 where the temperature thereof may be in the neighborhood of seventy-five to eighty degrees Fahrenheit (75°-80° F.). That juice in storage tank 10 is pumped through pipe 12 by pump 11 and through the flash pasteurizer 13 at a high pressure. The juice is heated in the pasteurizer 13 to a temperature in the range of about one hundred and ninety degrees Fahrenheit (190° F.) to two hundred and sixty-five degrees Fahrenheit (265 F.), and, for the purposes of illustration, may be there heated to a temperature of about two hundred degrees Fahrenheit (200° F.). Supply or inlet pipe or duct 14 feeds the pasteurized juice under high pressure to the tangential inlet at 64 for the explosion compartment 63, where it is discharged in a whirling spray about the circular walls of that compartment.

There is required evaporation of water in the orange juice in an amount of about two per cent (2%) in order to completely remove therewith the 0.04% of peel oil in vapor form. As a factor of safety, the apparatus may be adjusted to evaporate three per cent (3%) of the water content so as to assure complete removal of the oil. Heat given off by water as it is vaporized is approximately 1134 B. t. u.'s per pound of water, and thus the three per cent (3%) thereof to be vaporized for complete de-oiling will give approximately 34 B. t. u.'s. This requires reduction of the temperature of the liquid approximately thirty-four degrees (34°), which, with a starting temperature of two hundred degrees (200°), dictates a final temperature of about one hundred and sixty-six degrees (166°). In order to maintain this latter temperature, evacuation to an absolute pressure of 11.12" of mercury is required. The evacuation is accomplished by the steam jet 33, and the control of the degree of evacuation to that value may be automatically maintained by the diaphragm pressure regulator 36, or the pressure regulator 45, or by the regulation of the temperature of the condenser water as explained hereinafter.

With the maintenance of that degree of evacuation, the juice as it is sprayed through the tangential inlet at 64 will explode and about three per cent (3%) of the water content of the juice will evaporate along with complete evaporation of the lighter peel oil which has a higher vapor pressure. The mixture of vapors will pass up through the spaces between the arms of the support spider 48, between the floatation separator container 47 and the inner wall of chamber 21, and up to and into the tubes 27-27 of the reflux condenser unit 20. During this upward passage of vapors, tiny droplets of entrained juice may collect on the walls of the upper casing or shell section 23 to flow theredown toward the coned bottom 19, there to be remixed with the major portion of the water content and the juice solids, to be discharged out through the juice outlet conduit 16. The mixture of vapors of oil and water will condense on the inner walls of the condenser tubes 27-27, due to the chilling thereof by the flow of cool water through the jacket 25. The resulting condensate drips directly down from the bottom ends of the condenser tubes 27-27 into the open mouth of funnel 49, and, of course, the temperature of the cooling water and the length of the condenser tubes may be such as to assure complete condensation of those vapors in the condenser unit at the degree of evacuation maintained by the pressure regulator, so that

they will not be drawn upwardly into the top of the tower or collar 32 by the evacuation at steam jet 33.

In starting the operation of the de-oiling plant, the floatation separator container 47 will be filled with a body 65 of water up to the interface or "WL" level. As the mixture of condensed water and oil flows down into the funnel 49, it is discharged through the funnel tube 50 via the holes 52-52 at the bottom thereof, well beneath the surface of the body of water 65 in separator container 47, in lateral directions, as indicated by the arrows in Fig. 3. Since the oil is of less specific gravity, it will rise to the top of the body of water 65 to collect thereon at 66. As the quantity of water in body 65 is increased, it rises through holes 62-62 in the bottom of baffle tube 61 and flows out at the top intake end 54 of stand pipe 53, and thence from the discharge end 55 of the latter down into the bottom of the shell or casing to be remixed with the major portion of the water content of the juice and the juice solids, thereby constantly maintaining the original water content of the juice. The locations and the arrangements of the outlet holes 52-52 in the bottom of the funnel discharge tube 50 and the intake holes 62-62 in the bottom of the baffle tube 61, are so related as substantially to isolate one from the other, preventing any direct flow of oil condensate component from the funnel discharge into the baffle tube so that no oil will be returned to the juice with the water condensate.

The body 66 of oil on the top of the body 65 of water will gradually increase in volume until the "OL" level rises above the intake end 57 of stand pipe 56. Oil will then flow down stand pipe 56 out of its discharge end 58 into receptacle or cup 59, to be gravity fed therefrom by pipe 60 into oil receiver 67. This floatation separation of the oil is assured by the fact that the specific gravity of water is about eight and three tenths pounds per gallon (8.3 lbs. per gal.), while that of the peel oil is about seven pounds per gallon (7 lbs. per gal.).

Preferably the receiver 67 is provided with a quantity of water, down into which the bottom end 68 of discharge pipe 60 well extends to provide an effective water seal so that the vacuum in the tower shell will not be broken thereat. In order to accomplish this purpose, the length of oil discharge pipe 60 should be such that the degree of evacuation in the chamber 21 will raise the water in that pipe to a height of about twenty to twenty-two feet (20-22') above the water level in receiver 67. Overflow feed of oil condensate to the receptacle or cup 59 will gradually drive the water down discharge pipe 60 until the oil eventually is discharged at the bottom end 68 thereof into the body of water in the receiver 67 to rise and float upon the surface of the body of water therein. Cup 59 should be sufficiently higher above the water level in receiver 67 as to assure maintenance of a liquid seal with the oil level below the rim of that cup when pipe 60 becomes filled with oil to discharge into the receiver.

The de-oiled juice, including all of its water content, due to the re-mixture of the small percentage of water condensate (3%) therewith, will be fed by juice outlet conduit 16 to a suitable can filler mechanism of well-known type at 17. That de-oiled juice will there be mixed in suitable proportions with juice which has not been de-oiled (such as 50% of each) to reduce the oil content of the mixture to the desired degree. Such

admixture at the can filler 17 may be accomplished by feeding pasteurized juice which has not been de-oiled thereto for such admixture from any suitable separate source, or a by-pass conduit may be connected between pasteurizer 13 and can filler feed conduit 16 and have associated therewith suitable valve mechanism to proportion the flow of pasteurized juice through that by-pass and up through the pipe 16 to obtain the desired proportions of de-oiled and oil-containing juice at the can filler. If the proportions thereof are to be fifty per cent of each, one-half of the pasteurized juice will be by-passed directly from pasteurizer 13 to the conduit 16, and the other half will be forced up through pipe 14 to be fed to the de-oiler 15.

In the modification shown in Figs. 4 to 7 inclusive, de-oiler 15 comprises a tower shell 180 which is preferably of constant diameter throughout its entire height, including condenser unit 20. As a result, collecting funnel 149, serving as a top for separator container 47, may be of smaller diameter than the bottom of the condenser unit. Accordingly, in order to assure flow of all condensate drippings from the bottom of condenser unit 20 into the floatation separator container 47 via its discharge tube 150 preferably provided with a lateral outlet 152 by elbowing the bottom of that tube, such funnel structure may be supplemented with additional collecting means. This additional collecting means may comprise a ring 69 in the form of a truncated cone having its upper flared edge of a diameter greater than the diameter of a circle encompassing the outer row of condensation tubes 27-27 of condenser unit 20, and with its lower smaller end supported by suitable brackets 70-70 upon the top of separator container 47 or funnel 149. The oil outlet for the container 47 comprises a pipe fitting 71 communicating with the interior of the container through the side wall thereof and connected by a union coupling 72 to the end of discharge pipe extending through the side wall of the shell 180.

The separator container 47 is preferably supported upon a finned centrifugal separator ring 248 having spiraled fins or blades 73 to provide swirling of vapor mixture and entrained juice droplets when passing upwardly therethrough so as to throw the latter out against the inner wall of the shell. The separator supporting ring 248 also preferably includes a circumferential flange 74 which extends therebelow with its bottom edge seated within an upwardly cupped circumferential ledge 75. Entrained juice droplets, as they collect on the inner wall of the shell 180, will run down into the circumferential ledge 75 and eventually overflow the latter down into the bottom of the shell, there to admix with the major portion of the juice for discharge out conduit 16. Of course, a plurality of spaced apart brackets may be used in lieu of cupped ledge 75 for support of blade ring 248, with liquid flow down the inner shell wall therebetween being permitted.

The juice inlet or supply duct or pipe 14 extends substantially tangentially completely through the side wall of shell 180 into compartment 63, and, preferably, terminates therein in a flared or fan-shaped discharge nozzle 76 so as to assure the production of a spray of juice against the inner wall of the explosion compartment.

It is also possible to control the degree of evacuation by maintaining the water in the jacket of the reflux condenser at a temperature 75

at which some of the vapors rising in the condenser tubes will pass upwardly to the steam jet evacuating means to overtax it to an extent which results in accurate maintenance of the degree of evacuation. This can be accomplished by employment of a flow controlling valve in the cooling water supply pipe, operated either as a thermostatic valve with its thermostatic bulb element immersed in the cooling water or located in the vapor space above or below the condenser, or as a diaphragm vacuum regulator with its diaphragm chamber evacuating tube connected to the vapor space below or above the condenser. For example, as indicated in Fig. 8, the apparatus of Fig. 3 may be modified by omitting regulator 45 and its connecting pipe and reversing the flow of cooling water, in through lower pipe 39 and out through upper pipe 29. A flow controlling valve 77 may be mounted in the cool water inlet pipe 38. Portion or casing 78 of valve 77 may house a spring loaded valve stem connected to a Sylphon or bellows element the interior of which may be communicated by duct 79 with the usual thermostatic bulb element or capsule (not shown), together containing a thermally expansive liquid. The construction and operation of such a thermostatic valve is so well known as to need no detailing here. That bulb element or capsule may then be immersed in the cooling water, as by being located at a selected point within jacket chamber 25, such as at 80, or even in the upper pipe 29, serving as the outlet. If desired, the capsule or bulb element may, instead of being immersed in condenser cooling water, be located in the vapor space, either below condenser 20 in casing section 190, or above the condenser within dome 31. Valve 77 may be of the vacuum operated type, such as valve 36, with the casing 78 housing the structure of valve 36 shown in Fig. 2, and with its chamber evacuating tube 79 connected either to the vapor space below or above condenser 20, either to casing section 190 or dome 31.

It will thus be seen that the objects set forth above, among those made apparent from the preceding description, are efficiently attained and, since certain changes may be made in the above construction and different embodiments of the invention could be made without departing from the scope thereof, it is intended that all matter contained in the above description or shown in the accompanying drawing shall be interpreted as illustrative and not in a limiting sense.

It is also to be understood that the following claims are intended to cover all of the generic and specific features of the invention herein described, and all statements of the scope of the invention which, as a matter of language, might be said to fall therebetween.

Having described my invention, what I claim as new and desire to secure by Letters Patent is:

1. Apparatus for separating liquids of different specific gravities and vapor pressures comprising, in combination; a hollow, closed, substantially vertical casing; means to draw a vacuum in said casing; discharge means for heavier liquid in the bottom of said casing, an explosion area intermediate the tops and the bottom of said casing to effect initial vacuum distillation separation, inlet means to supply to said area a heated mixture of the heavier liquid and lighter liquid, an open-bottomed condenser means in the top of said casing to condense vapors of a rich mixture of the lighter liquid and a fraction of

the heavier liquid as they rise from said explosion area, floatation separator means mounted in said casing intermediate said condenser means and the explosion area to collect drippings of mixture condensate from the former, means providing fluid passage within said casing between the explosion area and said condenser means, means to deliver the lighter liquid after floatation separation above an interface level in said separator means out of the latter and said casing, means to deliver the heavier liquid after floatation separation from below the interface level directly back into the bottom of said casing for remixing with initially separated heavier liquid for discharge therewith, collecting means located between said floatation separator means and said condenser means and being of a lateral dimension greater than the open bottom of said condenser means, provision being made for vapor passage from the explosion area to said condenser means past said collecting means, said collecting means comprising a funnel top for said floatation separator means, and a duct leading from said funnel top down into said floatation separator means and having an outlet below the interface level.

2. The apparatus as defined in claim 1 characterized by the provision of said floatation separator means as a cylindrical container spaced from the walls of said casing and closed off at the top by said funnel with the latter arranged beneath said condenser means.

3. The apparatus as defined in claim 2 char-

acterized by the provision in said floatation separator means of a heavier liquid delivery duct having an intake at the interface level, and baffle means isolating the delivery intake from lighter liquid collectable above the interface level, said baffle means having heavier liquid intake below the interface level and above the outlet of the duct leading from said funnel top.
